UNITED STATES PATENT OFFICE.

RICHARD C. LUDLOW, OF ST. LOUIS, MISSOURI.

FLY-SCREEN.

SPECIFICATION forming part of Letters Patent No. 244,637, dated July 19, 1881.

Application filed April 2, 1881. (No model.)

To all whom it may concern:

Be it known that I, RICHARD C. LUDLOW, a citizen of the United States, resident at St. Louis and State of Missouri, have invented 5 certain new and useful Improvements in Fly-Screens; and I do hereby declare the following to be a full, clear, and exact description of the invention, such as will enable others skilled in the art to which it appertains to make and 10 use the same, reference being had to the accompanying drawings, and to letters or figures of reference marked thereon, which form a part of this specification.

Figure 1 is a front view of my device. Fig. 15 2 is a vertical section, and Fig. 3 is a horizontal section.

This invention relates to improvements in screens for windows, known as "fly-screens;" and it consists in the improved features of construction and combination hereinafter fully described, and particularly pointed out in the claim.

Heretofore much annoyance has been experienced arising from the necessity of putting 25 in and taking out screens whenever it is desired to cover or uncover the open space of the windows with the construction now in use, all of which is avoided by the present device.

In the annexed drawings, A is the window-frame having the usual top and bottom sashes, 30 B C.

Secured to the inside strips, D D, are the rails E E, somewhat longer than the space made when the lower sash is raised. These 35 rails have the tongues e e, and are divided into upper and lower portions, a and b, by the outwardly, downward, oblique kerfs, c, the lower portions, b b, being rigidly affixed to the strips, and the upper portions, a a, pivoted at d d, 40 these pivots being at such points that when the lower sash is up and the upper portions turned out at right angles they will strike the the bottom rail of the sash.

F is the screen, having in its side edges the 45 grooves f f fitting the tongues e e, and at its

bottom, on the inside, the groove f', which may be a simple groove or formed by an ornamental molding.

In putting the screen in, the lower sash is raised and the pivoted portions of the side 50 rails turned with their upper ends inward. The screen is taken with its outer side up, and with its lower side forward is slipped onto these upper portions, the tongues fitting the grooves. It is slid on for nearly the length of these upper portions, and then is swung up, these 55 turning down to their places when the screen is lowered to place. To take the screen out the operation is reversed.

The groove at the bottom facilitates lifting 60 without the trouble of hunting for the lift, and is equally applicable to a window-sash.

When it is desired to have the lower part of the window open without taking the screen away the latter is pulled up, turned down at 65 right angles, and its lower end caught under the sash, where its weight will hold it.

The screen may be placed on the outside, if desired.

A pivoted side strip, in combination with a 70 sash having grooved edges, is not broadly new, and protection is asked only for the improved construction hereinafter claimed.

I claim—

In a fly-screen for windows, the rails E, having 75 the tongues e, and located below the upper sash-frame, the portion a being pivoted to the window-frame, and the portion b being rigidly secured thereto, in combination with the screen F, having grooved edges to receive the tongues 80 e, whereby the screen may be drawn up and placed in a horizontal position without removing it from the rails, substantially as shown and described.

In testimony whereof I affix my signature 85 in presence of two witnesses.

RICHARD C. LUDLOW.
